CLAIM

The ornamental design for a humeral implant, as shown and described.

DESCRIPTION

FIG. 1 is a top perspective view of an embodiment of a humeral implant of our design;

FIG. 2 is a bottom perspective view of the design of FIG. 1;

FIGS. 3-6 are side views of the design of FIG. 1;

FIG. 7 is a top view of the design of FIG. 1; and

FIG. 8 is a bottom view of the design of FIG. 1.

FIG. 9 is a top perspective view of another embodiment of a humeral implant of our design;

FIG. 10 is a bottom perspective view of the design of FIG. 9;

FIGS. 11-14 are side views of the design of FIG. 9;

FIG. 15 is a top view of the design of FIG. 9; and,

FIG. 16 is a bottom view of the design of FIG. 9.

All features illustrated in broken lines form no part of the claimed design.
